UNITED STATES PATENT OFFICE.

JAMES A. MOXEY, OF CHICAGO, ILLINOIS, ASSIGNOR TO INTERNATIONAL HARVESTER CORPORATION, A CORPORATION OF NEW JERSEY.

FIFTH-WHEEL.

1,139,703.

Specification of Letters Patent.

Patented May 18, 1915.

Application filed October 24, 1913. Serial No. 797,039.

To all whom it may concern:

Be it known that I, JAMES A. MOXEY, a citizen of the United States, residing at Chicago, in the county of Cook and State 5 of Illinois, have invented certain new and useful Improvements in Fifth-Wheels, of which the following is a full, clear, and exact specification.

This invention relates to fifth wheels.

10 Among users of the lighter types of horse drawn vehicles, known as farm wagons, a gradual demand has arisen for fifth wheels. Such a wheel, to be practical, must have as prime essentials simplicity, durability and economy of construction 15 without sacrificing in any way the important advantages of the more expensive forms of fifth wheels.

It is the object of my invention to provide 20 a fifth wheel admirably suited for such uses, and to improve the design, construction and operation of a device of this class in a manner to render it sparingly requisite in the use of material, highly efficient 25 in the performance of its functions, and inherently strong and rugged in formation.

Moreover, it is my object to produce such 30 a device which will be capable of attachment to a vehicle without the necessity of employing further fastening means than the bolts ordinarily used for securing the wearing plates to the sandboard and bolster, and in this way to maintain unimpaired the 35 natural strength of the bolster and sandboard by reason of the absence of extra bolt holes and the like; and finally it is my object to so arrange the fifth wheel with relation to the sandboard and bolster of the 40 vehicle that a general distribution of the strain will result and thereby danger of the metal in the fifth wheel cutting into the wooden bolster and sandboard at over-burdened points will be eliminated.

45 These objects I accomplish by means of two peculiarly formed plate members constituting the fifth wheel, which coöperate in a novel manner with the wearing plates of the bolster and sandboard to produce a 50 smooth continuous bearing surface, and also coöperate directly with the sandboard and bolster to engage the vertical sides thereof and securely reinforce the same, obtaining in an effective manner an equal 55 distribution of strain on these parts.

One form which my invention may assume is exemplified in the following description and illustrated in the accompanying drawing, in which—

Figure 1 shows a plan view of a portion 60 of a bolster and sandboard having my improved fifth wheel applied thereto; Fig. 2 shows a side elevation of the same; Fig. 3 shows a vertical cross sectional view taken on the line 3—3 of Fig. 2; Fig. 4 shows a 65 vertical central longitudinal sectional view of a bolster and sandboard having my device applied thereto; and Fig. 5 shows a detached plan view of one of the wheel members of my improved fifth wheel. 70

In the drawings is shown a portion of a front axle 10, a sandboard 11 carried on the axle, and a bolster 12 mounted on the sandboard, all of said parts being connected together in the ordinary way by means of a 75 king bolt 13. Wearing plates 14 are provided for the adjacent surfaces of the bolster and sandboard, and for securing these plates in proper position the usual bolts 15, vertically extended through the bolster or 80 through the sandboard, are provided.

The fifth wheel comprises two parts, an upper member 16 and a lower member 17, similar in shape. The body portion 18 of each of these members is ring shaped, and at diametrically opposite points thereon depressions 19 are formed that receive the wearing plates 14, and thus a smooth continuous bearing surface is effected. In the present instance these depressions are in 90 the form of offset portions, and the adjacent bolster and sandboard members are slotted in order to accommodate said offset portions which, it will be seen, occupy positions between the wearing plate and the 95 bolster in one case and the wearing plate and sandboard in the other. Centrally of each ring are two right angular walls 20, spaced apart to receive between them the bolster or sandboard, as the case may be, 100 and strengthening ribs 21 are extended between the right angular walls and the adjacent portion of the ring.

By arranging the plate members of the fifth wheel in the manner shown I find that 105 the same bolts 15, that are used to secure the wearing plates in position, may be employed as the sole fastening means for the fifth wheel members, and for this purpose I have provided openings 22 in the depressed 110

portions of each of the wheel members to receive said bolts. The right angular wall members 20, it will be noted, securely embrace the vertical surfaces of the bolster and sandboard and, because of the large area which they cover, it is obvious that said bolster and sandboard will be rigidly reinforced, and that the strain applied to them in operation will be fairly and equally distributed over a maximum of surface. The large opening in the center of each of the wheel members affords an unrestricted space for the king bolt.

By an ingenious arrangement the ring portions are made to coöperate with the wearing plates, and much material is thereby saved in the construction of the wheels. The wall members, with their strengthening ribs, make for a sturdy construction of the entire device, and by having them embrace the bolster and sandboard, these latter are so effectively reinforced that the need of extra bolts is overcome and the whole design is so planned that the same bolts used for securing the wearing plates in position can be utilized as the sole fastening means for the fifth wheel. Much that is undesirable in the practical application of fifth wheels is thereby done away with, for it is well-known that to provide openings for bolts, or to drive screws into the wooden parts, tends only to weaken the none too durable strength of the bolster and sandboard. The large openings formed in the central portions of the sandboard and bolster to receive the king bolt naturally render those members weakest at these and adjacent points, and it is here that a majority of the breakage occurs in wagons. In my device much of this breakage is prevented by the wall members, which have the effect of ironing and thereby reinforcing said bolster and sandboard at the critical points thereon. With the vertical wall members 20 held securely against the bolster and sandboard and covering a large area of their surfaces, a maximum distribution of the strain is secured as distinguished from the concentrated strain applied by other devices of this class. Cutting into the wood and excessive wear on vital parts of the bolster and sandboard are therefore not present in my device. A fact worthy of notice is that my device is admirably adapted for ordinary farm wagons which, as is well-known, have reached a standard in construction that nearer approaches uniformity than that of any other line of vehicles now in use. Therefore, by producing a fifth wheel that will coöperate with the bolster, sandboard and wearing plates, and be held in place by the same fastening means as used for these wearing plates, and by embracing the vertical surfaces of the adjacent wooden parts securely reinforce them, I have not achieved an isolated design with limited uses, but,

on the contrary, a device results which, with but a few slight changes in dimensions, will have a general and universal application to farm wagons.

While I have shown and described but one form of my device, it is obvious that it is susceptible of many modifications, and therefore changes may be made in the details of construction without departing from the spirit of my invention as disclosed in the appended claims.

What I claim as my invention, and desire to secure by Letters Patent, is:

1. In a vehicle, a bolster, a sandboard, wearing plates for the adjacent surfaces thereof, and an upper and a lower wheel member coöperating with the surfaces of said wearing plates to form a fifth wheel.

2. In a vehicle, a bolster, a sandboard, wearing plates for the adjacent surfaces thereof, and an upper and a lower wheel member extending between said bolster and sandboard to either side thereof and forming smooth bearing surfaces with said wearing plates.

3. In a vehicle, a bolster, a sandboard, wearing plates for the adjacent surfaces thereof, and an upper and a lower wheel member extending between said bolster and sandboard to either side thereof and forming smooth bearing surfaces with said wearing plates and held in position by said wearing plates.

4. In a vehicle, a bolster, a sandboard, wearing plates therefor, fastening means for said wearing plates, and a fifth wheel held in place by said fastening means.

5. In a vehicle, a bolster, a sandboard, wearing plates therefor, a king bolt, bolts at either side of said king bolt for holding the wearing plates in position, and a fifth wheel held in place by said bolts.

6. In a vehicle, a bolster, a sandboard, wearing plates therefor, an upper and a lower wheel member extending between the wearing plates and the adjacent sandboard or bolster.

7. In a vehicle, a bolster, a sandboard, wearing plates therefor, a fifth wheel comprising upper and lower members extended between the wearing plates and the adjacent sandboard or bolster, and bolts extended through said bolster or sandboard for holding the wearing plates and wheel members in position.

8. In a vehicle, a bolster, a sandboard, wearing plates therefor, a fifth wheel comprising upper and lower members extended between the wearing plates and the adjacent sandboard or bolster and provided with depressed portions to receive the wearing plates and effect a smooth bearing surface therewith.

9. In a vehicle, a bolster, a sandboard, wearing plates therefor, a fifth wheel com-

- prising upper and lower wheel members ex-
tended between the wearing plates and the
adjacent bolster or sandboard and having
depressed portions to effect a smooth bear-
ing surface with said bearing plates, and
fastening means extending through said de-
pressed portions and into the adjacent sand-
board or bolster for holding said wheel
members in position. 5
10. In a vehicle, a bolster, a sandboard,
a king bolt for said bolster and sandboard,
a fifth wheel comprising two ring-shaped
members each provided with wall members
to embrace opposite sides of said bolster or
15 sandboard and open at their bottoms to
permit the king bolt to reside freely be-
tween, and fastening means extending
through the annulus of each of said ring-
shaped members and connected with the bol-
ster or sandboard. 20
11. In a vehicle, a bolster, a sandboard, a
king bolt for said bolster and sandboard, a
fifth wheel comprising two ring-shaped
members each provided with diametrically
25 extending wall portions open at their lower
ends and arranged to embrace opposite sides
of said bolster or sandboard in a manner
to permit the king bolt to reside between
them, and strengthening ribs extending be-
30 tween the wall portions and annuli of the
ring-shaped members. 35
12. In a vehicle, a bolster, a sandboard,
wearing plates therefor, a fifth wheel com-
prising two ring-shaped members each pro-
35 vided with wall portions to embrace oppo-
site sides of said bolster or sandboard and
provided with depressed portions to coact
with said wearing plates, and bolts extend-
ing through said sandboard or bolster for
40 holding said wheel members in position. 45
13. In a vehicle, a bolster, a sandboard,
wearing plates therefor, a fifth wheel com-
prising two members each provided with
wall portions to embrace opposite sides of
45 said bolster or sandboard, said wheel mem-
bers coöperating with the wearing plates
to form continuous smooth bearing surfaces
and held in position by the same fastening
means employed for the wearing plates. 50
14. A fifth wheel comprising two mem-
bers each including a ring portion having
depressed surfaces at diametrically oppo-
site points thereon. 55
15. A fifth wheel comprising two mem-
bers each including a ring portion having
its annulus depressed at opposite points,
and spaced wall members arranged centrally
thereon. 60
16. A fifth wheel comprising two mem-
bers each including a ring portion having
its annulus depressed at opposite points,
and spaced wall members arranged cen-
trally thereon, and strengthening ribs ex-
tending between said wall members and ad-
jacent part of the ring portion. 65
17. A fifth wheel comprising two mem-
bers each having a ring portion with de-
pressed surfaces at opposite points thereon,
spaced wall members centrally arranged
thereon, and strengthening ribs extending
70 between the wall members and adjacent part
of the ring portion, said depressed portions
being provided with openings to receive fas-
tening means. 70

In testimony whereof I affix my signa- 75
ture, in the presence of two witnesses.

JAMES A. MOXEY.
